APPARATUS FOR FILLING CONTAINERS

Clarence Freemont Carter and James A. Reynolds,
Danville, Ill.; said Reynolds assignor to said
Carter

Application January 8, 1948, Serial No. 1,194

2 Claims. (Cl. 226—49)

1

This invention relates to a method and apparatus for filling containers with comminuted solids. More particularly it relates to an automatic apparatus for filling envelopes with powdered or granular solids, and then sealing the envelopes thus filled.

It is an object of the invention to provide an apparatus which automatically places envelopes in filling position, opens them to receive the powder or granules, empties a measured charge of powder or granules into the envelope, transfers the envelope to a synchronized conveyor, seals the envelope, and discharges a predetermined number of filled and sealed containers at one or more stations ready for packaging for shipment.

A further object is to provide an improved envelope positioning device whose movement is exactly synchronized with the movement of a hopper and dial carrying the filling mechanism.

Other objects will become apparent from the following description of the apparatus, one embodiment of which is illustrated in the accompanying drawings.

Figure 1 is an elevation in section through the center line of the filling portion of the machine.

Figure 2 is a perspective partly in section of the vacuum port means.

Figure 3 is a plan view with certain portions cut away, of the filling portion of the machine and part of the conveyor system.

Figure 4 is a perspective view partly in section of the mechanism for accomplishing the envelope mechanism feed motion.

Figure 5 is a perspective of one envelope suction block and opening fingers.

Figure 6 is a side view of one of the measuring valves.

Figure 7 is a side view of the sealing and folding unit.

Figure 8 is a plan view of a portion of the machine shown in Figure 7.

Figure 9 is a plan view of the entering section of the sealing chain.

Figure 10 is the elevation of the detail shown in Figure 9.

Figure 11 is a view along the line 11—11 on Figure 9.

Figure 12 is a view along the line 12—12 on Figure 9.

Figure 13 is an elevation of one of the envelope pockets.

Figure 14 is a plan view of the end of the sealing chains and envelope conveyor.

Figure 15 is an elevation of the portion shown in Figure 14.

2

Figure 16 is a diagrammatic sketch of the drive system.

Refer now to the drawings for a detailed description of the machine and its operation.

5 Machine frame 1 supports the bracket 2 in which is clamped stationary spindle 3 which is hollow for a portion of its length. About this spindle 3 dial 4 rotates in a counter-clockwise direction. Dial 4 is journalled on bearing 7 and supported by thrust bearing 5. Driving gear 6 is fixed to the lower end of the dial hub 4' and is driven in synchronism with conveyor 12 by means of pinion 13 (see Fig. 16) fixed to sprocket 14, both running on shaft 17 and connected by chain 15 53 to sprocket 15 keyed to conveyor shaft 16. The machine drive is from motor 11 through variable speed pulley 17 and belt 18 to gear box 19 (speed reducer). The slow speed shaft 19' on gear box 19 is coupled to longitudinal shaft 20 through sprockets 21 and 22 and chain 23. This longitudinal shaft 20 drives the sealing device generally indicated as 24 on Figure 7, through a pair of beveled gears 25, sprocket 26 on shaft 21 and chain 28 to sprocket 29 on shaft 30. Shaft 20 also drives pressure belt 31 and sealing chain 32 through a pair of beveled gears 34 and vertical shaft 35, sprocket 37 engaging chain 32 and passing around idler sprocket 36. Chain 33 is also driven by shaft 20 through the pair of beveled gears 34 and a spur gear 38 on vertical shaft 35. Spur gear 38 drives spur gear 39 on vertical shaft 40 which drives sprocket 42 engaging chain 33 which passes around idler sprocket 41. Pressure belt 31 is driven by a sprocket 43 on vertical shaft 35', engaging chain 34 to sprocket 45 fixed to vertical shaft 46 on the lower end of which is drive pulley 47. Pressure belt 31 passes around idler pulley 48 which runs on vertical shaft 49 fixed in arm 50 (Fig. 3) which is supported on post 51.

40 Dial drive and mechanism feed motion is obtained from the opposite end of slow speed shaft 19' on the gear box 19 through beveled gears 52, vertical shaft 16, sprocket 15, chain 53 to sprocket 14 which is fixed to pinion 13 and rotates on shaft 17. The envelope feed motion mechanism is obtained from dial gear 6 through idlers 54 and pinions 55.

45 The envelope feed mechanism will now be described with special reference to Figures 1, and 3 to 5.

50 Empty envelopes are loaded into two magazines generally indicated as 56 and 57, each magazine is fixed to a slidably mounted plate 58. The motion of each magazine is similar and only 55 one will be described in detail. The envelopes

are fed in pairs, one from each magazine to a pair of envelope suction blocks on the rotating dial. The motion of cam 59 is synchronized with the movement of dial 4 through shaft 60, gears 55, idlers 54 and gear 6. This cam 59 imparts a reciprocating motion to slide 58 through roller 61, slide 62 and link 63. Spring 64 resting against base or housing 65 and thrusting against slide 62 causes roller 61 to follow cam 59. Slide 58 is carried in slideway 66 which is given an oscillating motion about pivot 71 by means of cam 67, rocker arm 68 pivoted at 68', and link 69. The slide 58 is held in position in the slideway 66 by means of plates 70. This same oscillating motion is imparted to the other magazine 57 through link 72 pivotally connected at 73 and 74 to the forward ends of the two slideways 66. The reciprocating motion of slide 58 coupled with the oscillating motion of its slideway 66 causes the envelope magazine to travel in an elliptical path somewhat flattened at the forward end.

The shape of cams 59 and 67 and the timing relative to each other and to dial 4 is such that the envelope magazine moves rapidly forward to contact an appropriate suction block 75 during its rotation about the spindle 3. At the time of contact of the envelope with the suction block for approximately 5° of the dial rotation the sideward motion of the envelope magazine is synchronized with the rotation of the dial. The envelope magazine then backs sharply away and repeats the cycle. Thus during each cycle an envelope is simultaneously placed in position on each of two suction blocks.

It is an advantage of this invention that the movement of the mechanism is synchronized as described with the movement of the dial so that the envelopes are placed squarely and accurately on the suction block and held there until subsequent action, hereinafter described, maintains them on the suction block. The timing is such that the movement of the magazines and the suction blocks must always correspond and each envelope must necessarily be placed in its intended position.

Weight of the envelope follower 76 sliding in bearings 77 keeps a supply of empty envelopes in position at the forward end of the magazine. The envelopes are prevented from sliding out of the envelope magazine until gripped by suction block 75 by pointed pins 78 protruding slightly inside the magazine wall 79.

As the suction block 75 carrying the empty envelope rotates past air-fed nozzle 80, (Fig. 3), a sharp blast of air is directed against the envelope flap and downward into the envelope thus blowing it open. Coincident with this, fingers 81 pivoted at 82 are pulled together by spring 83 as rollers 84 at the extremities of the finger arms drop off of cams 85 and 86. Pressure of the outer end of fingers 81 against the back of the open envelope maintains it in an open position.

Above each suction block 75 and in line with the open envelope is a measuring valve generally shown as 87 (see Fig. 6) supported by framework 88 which is fixed to dial 4 and thus rotates with it. This valve 87 is supplied with powdered or granular material from hopper 89 supported by framework 88.

At approximately point A (Fig. 3), the upper gate 90 is opened by the action of stationary cam 91 acting against roller 92 fixed to arm 93 which is clamped to shaft 94 on which gate 90 is

fixed. Powder or granular material then flows from hopper 89 through tube 95 into measuring chamber 96 filling it to capacity. At point B roller 92 drops off of cam 91 and comes into contact with upper cam 97 forcing it down and closing gate 98 thus cutting off the flow of material into the measuring chamber.

At approximately point C the lower gate 98 of chamber 96 is opened by roller 99 riding under stationary cam 100. Roller 99 is fixed on arm 101 which is clamped to gate shaft 102. As gate 98 opens, the charge of material contained in the measuring chamber 96 falls through funnel 103 and into the envelope below. At point D gate 98 is closed by the action of spring 104 as roller 99 rides off of the end of cam 100 and the filling cycle is repeated.

As the suction block approaches the discharge position, fingers 81 are opened by rollers 84 riding up over cams 85 and 86 thus allowing the envelope to close.

Movement of conveyor 12 is synchronized with dial 4 so that each suction block coincides with an envelope pocket 105 on conveyor 12, at the point of tangency (approximately point A). As the dial rotates and the conveyor 12 moves forward, the filled envelope is placed between fingers 106 and rests upon fingers 107. Stationary guide rod 108 strips the filled envelope from the suction block as the vacuum is released as hereafter described and the conveyor continues to move forward carrying the envelope with it.

Pressure belt 31 (Figs. 9, 10, 11) is driven in unison with the conveyor 12 and held against the surface of the envelope pockets by pressure rollers 109 thus pressing the envelope just below the top, tightly against the back plate 110 of the envelope pocket 105 during its passage through the sealing and folding device, thus obviating any slippage of the envelope which would cause an imperfect fold and seal. The envelope is held by this pressure belt until it enters and is gripped by sealing chains 32 and 33.

The sealing and folding mechanism is similar to other devices used for this purpose throughout the field. When desirable, a heat sealing unit may be substituted for the gluing device as illustrated herein.

As the envelope carried in the envelope pocket 105 progresses forward, turnover 111 (Figs. 7-8) turns the envelope flap to a horizontal position with its inner face uppermost in order to pick up a film of glue from glue wheel 112 which is supplied with glue by rollers 113 and 114 rotating in glue pot 115. The glued envelope then progresses to the fold over guide 116 which turns the glued flap downward into its final position. The flap is held down by plate 117 until it is gripped between sealing chains 32 and 33. Sealing chains 32 and 33 moving at the same linear speed as the envelope, press the glued flap tightly against the envelope. Length of travel of the envelope between the sealing chains is such that sufficient time is allowed for the glue to set. The sealing chain 32 in contact with the envelope is backed up by fixed idler 118, supported on bracket 119 and framework 120. Sealing chain 33 in contact with the backside of the envelope is pressed against sealing chain 32 by idlers 121 mounted on the ends of the equalizing bar 122 which is pivoted at the extremity of swinging arm 123. Spring 124 rotates arm 123 about its pivot 125 thus supplying pressure to the back of chain 33 in contact with the envelope. The

sealed envelope emerges from the sealing chains and is carried around the end of the conveyor as it passes over idler sprockets 133 and is held in place by guide rods 126 to point E (Figs. 11, 14 and 15). Here arm 127 pivoted on shaft 128 fixed to the envelope back plate 110 comes into contact with stationary rollers 129 and is cammed sharply outward kicking the filled envelope clear of the conveyor pocket and into discharge chute 130. As arm 127 passes beyond the cam rollers 129 torsion spring 131 returns it to its original position.

If desirable one-half of the envelope pockets may be discharged at one point and the other half at a second point at a further position along the conveyor by placing kicker arm 127 on half of the envelope pockets so that it will pass over rollers at point E but will strike a similar roller at point F. A similar arrangement may be made for several discharge points if desirable. Also the envelope pockets may be arranged so that groups of any desired number of envelopes will be discharged in succession at one point, and the following group of a similar number will pass by this point and be discharged at a succeeding point or points thus allowing an interval during which the operator may unload the discharge chute. In view of the rapidity with which the envelopes are discharged on a machine such as described having 12 suction blocks, this interval between discharges may be necessary to give the operators time to keep up with the operation. A machine of this size has the capacity of over 200 filled envelopes per minute.

The conveyor continues beyond the final discharge point F and passes around the driving sprockets 132 driven by vertical shaft 16. Variation in the length of sealing chains 32 and 33 is accommodated by the adjustable coupling 134.

Envelope pockets 105 are supported by rollers 135 mounted on pins 136 and rolling on track 137.

The level of powdered or granular material is maintained at the desired height in the hopper 89 by means of valve shoe 138 which closes off supply spout 139 when the material reaches the desired level.

Slack in conveyor chain 140 is taken up by set screw 141 pressing against bearing 142 in which is mounted the shaft 143 for idler sprockets 133.

Suction cups 144 on the face of block 75 are connected to a source of vacuum through chambers 145 (Fig. 1) and hollow shaft 146 of spindle 3. When ports 147 in bushing 148 are in alignment with chamber 145, they are uncovered by block 149, permitting vacuum to be drawn through groove 150 in spindle 3. The location and shape of this block 149 is such that vacuum is drawn on the suction cups beginning at the moment when the suction block is in line with the envelope magazines, thus picking up empty envelopes from the magazines and carrying them around with the rotating dial until approximately point A at which time the vacuum is cut off by block 149 covering ports 147. Port 147 is then open to atmosphere as it passes groove 151 which communicates with aperture 152 in shaft 3.

Having described a preferred apparatus and method, it should be understood that the invention is not limited to the exact details illustrated and described.

6
We claim as our invention:

1. An envelope filling machine comprising a support, a continuously rotatable dial mounted thereon, envelope supplying means mounted on said support at a fixed station adjacent the dial, a plurality of envelope grasping and holding means on said dial; said supplying means comprising a magazine mounted for limited movement, means for moving said magazine forwardly toward and into envelope engaging relationship with said grasping means, means for moving the magazine in a limited arc in the direction of travel of said dial and at the same rate of speed, means for moving said magazine away from said dial and returning it to its original position; means actuating said grasping means while in envelope engaging relationship with said magazine, means for opening said envelope, means for filling said envelope, and means for removing filled envelopes from said dial.

2. An envelope filling device comprising a support, a continuously rotatable dial mounted thereon, a plurality of envelope grasping means on said dial, envelope supplying means mounted on said support at a fixed station, said envelope supplying device comprising a magazine-bearing member mounted for reciprocation and limited lateral movement, said member being pivotally supported on said support at the end remote from the dial, a magazine mounted on said member, a first cam imparting reciprocal motion to said member, a second cam mounted adjacent the feed end of said magazine to impart limited lateral oscillatory motion to the end of said member adjacent the dial, driving means for said dial and said cams, said means imparting synchronous movement to said dial and said supplying means, whereby said magazine is moved forward into envelope engaging relationship with said grasping means and simultaneously moved laterally in the direction of movement of said continuously moving dial, is then moved away from said dial and back to the starting position, means for actuating said grasping means when in envelope engaging relationship to said magazine, means for opening said envelope, means for holding it open, means for filling said envelope, and means for removing filled envelopes from said dial.

CLARENCE FREEMONT CARTER.
JAMES A. REYNOLDS.
